UNITED STATES PATENT OFFICE.

HENRY FAIRBANK, OF LONDON, ENGLAND, ASSIGNOR OF ONE-HALF TO DOUGLAS STEWART MAULEVERER BROWN, OF WEST HAMPSTEAD, LONDON, N. W. 6, ENGLAND.

LOCKING DEVICE FOR INTERENGAGING SCREW-THREADED ELEMENTS.

1,404,105.

Specification of Letters Patent. Patented Jan. 17, 1922.

Application filed January 31, 1921. Serial No. 441,443.

To all whom it may concern:

Be it known that I, HENRY FAIRBANK, a subject of the King of England, residing at Wood Green, London, England, have invented certain new and useful Improvements in Locking Devices for Interengaging Screw-Threaded Elements, of which the following is a specification.

This invention relates to locking devices for securing two elements, which inter-engage by screwing one into the other, against accidental movement in the unscrewing direction. The invention is particularly applicable to constructions wherein the one element, for example a cap screw, that co-operates with another element, for example a base, has a face that approaches the other element when the first element is being screwed home on the second, and the invention has for its main object to provide that the locking device shall be released automatically when the one element is screwed home on the other.

When the invention is applied to a grease-box having a cap for forcing the grease out of the box, the cap is locked against unscrewing until the box has been emptied or nearly emptied by screwing the cap on to it as far as possible, whereupon the locking device is automatically released and the cap can be unscrewed for refilling the box.

The invention consists in the construction, arrangement and combination of parts described hereinafter and pointed out in the claims.

One embodiment of the invention is illustrated in the accompanying drawing, wherein—

Figure 1 is a bottom plan view of a grease-box with its locking pawl in its engaging position, and

Figure 2 is a vertical section through the grease-box taken on the line 4—4 in Figure 1.

Like reference letters indicate like parts throughout the drawings.

Referring to the drawing, a grease-box is shown comprising a base G and a screw-cap G¹ which is indicated as removed in Figure 1. A pawl H is pivoted at H¹ to the under side of the base G. This pawl has an operative nose H² which projects beyond the threaded periphery of the grease box base, as shown in Figure 1, and is shaped to corre-

spond to, and form a continuation of, one of the threads on the periphery of the base G. When the cap is on the base, therefore, the nose will engage the bottom of a thread of the cap. It will be seen that this nose is at such an angle that it will lie approximately at a cutting angle to the surface of the cap it engages, and thus will tend to dig into the same if the cap is rotated in the direction for unscrewing, but it will allow the cap to be rotated in the direction for screwing on to the base, as it will then trail around the inner face of the cap. To cause the nose to powerfully grip the cap it is so pivoted that its nose lies only a little to one side of a line passing through its point of pivoting, indicated at H¹, and radial to the axis of rotation of the cap; the pawl thus acts virtually as a wedge between the cap and the base and will grip the cap even if it be not provided with a sharp nose set at a cutting angle. To keep the pawl in operative position, a spring D is provided which spring bears at one end against a shoulder on the base, and at its other end against a lug H⁴ on the pawl. The pawl is also provided with a horn H³ which projects over a hole in the base in which a pin J is movable endwise. This pin is also situated in the base that its direction of endwise movement is parallel to the axis of pivoting of the pawl, its leading end is conical and the point of the end is in line with one side of the horn H³. It thus follows that if the pin J is advanced from the position shown in Figure 2, its conical end will force the horn H³ back and will thus release the operating nose H².

From the above description, it will be seen that the cap can be screwed on in the ordinary manner, but to permit it to be unscrewed, the pawl must be swung into an inoperative position in which it is released from the cap. For this purpose the non-tapered end of the pin J projects towards that face of the cap which is opposed to the base G, and thus when the cap is screwed home this face comes into contact with the pin and pushes it forward so that the pawl is brought into its inoperative position. The pin J is pushed sufficiently far down by screwing home the cap G¹ to bring the parallel portion of the pin into contact with the horn H³ after the pawl has been swung to the inoperative position, so that there is no tend-

ency for the pressure of the pawl to return the pin to its withdrawn position. The pin will thus remain in the advanced position and hold the pawl inoperative, whilst the cap 5 is unscrewed from the grease-box for refilling or for any other purpose. To render the pawl operative again, it is only necessary to push the pin back from the under side of the grease box. A circumferential rib J¹ on 10 the pin J limits its movement in both directions.

What I claim as my invention and desire to secure by Letters Patent is:

1. The combination, with two co-axial screw-threaded elements, whereof one is screwed on the periphery of the other and has a face that approaches the other when the said elements are being screwed home, of a spring-controlled pawl pivoted on one 20 of said elements to turn about an axis parallel with the axis of said elements, which pawl has a nose arranged normally to project beyond the element upon which it is mounted for engaging the co-operating element, which nose is so formed that it is 25 adapted to yield to movement of the one element relatively to the other in the screwing-on direction but to jam and hold the same in the unscrewing direction, and a 30 releasing member which is mounted on one of said elements and is arranged to lie in the path of said face on the co-operating element and, when the one element is screwed home to be forced by contact with said face 35 against the pawl in such direction as to move it into its disengaging position, the said releasing member being so constructed that it will remain in its in-operative position after the said face is withdrawn from 40 the releasing member.

2. The combination, with two co-axial screw-threaded elements, whereof one is screwed on the periphery of the other and has a face that approaches the other when 45 the said elements are being screwed home, of a spring-controlled pawl pivoted on one of said elements to turn about an axis parallel with the axis of said elements, which pawl has a nose arranged normally to project beyond the element upon which it is 50 mounted for engaging the co-operating element, which nose is so formed that it is adapted to yield to movement of the one element relatively to the other in the screwing-on direction but to jam and hold the same in the unscrewing direction, and a 55 releasing pin that is mounted on one of said elements and is arranged to be moved end-

wise by said face in a direction parallel to the axis of pivoting of the pawl when the 60 said elements are being screwed home, which pin has a cam-shaped end arranged to co-act with one side of said pawl, whereby the latter is driven into its disengaging position when the pin is advanced. 65

3. The combination, with two co-axial screw-threaded elements, whereof one is screwed on the periphery of the other and has a face that approaches the other when the said elements are being screwed home, 70 of a spring-controlled pawl pivoted on one of said elements to turn about an axis parallel with the axis of said elements, which pawl has a nose arranged normally to project beyond the element upon which it is 75 mounted for engaging the co-operating element, which nose is so formed that it is adapted to yield to movement of the one element relatively to the other in the screwing-on direction but to jam and hold the same in the unscrewing direction, a releasing pin that is mounted on one of said elements 80 and is arranged to be moved endwise by said face in a direction parallel to the axis of pivoting of the pawl when the said elements are being screwed home, which pin has a conical end arranged to co-act with 85 one side of said pawl so that the latter is driven into its disengaging position when the pin is advanced, and means for limiting 90 the travel of said pin in both directions. 95

4. In a lubricating device, the combination with an externally-threaded base-member having a hole therein, of a cap-screw 95 screwed thereon, a spring-controlled pawl pivoted on said base-member to turn about an axis parallel with the axis of rotation of the cap-screw, which pawl has a nose arranged to engage the cap-screw, said nose being so formed that it is adapted to yield 100 to movement of the cap-screw in the screwing-on direction, but to jam and hold the same in the unscrewing direction, and a releasing pin that is mounted on said base-member and is arranged to move endwise in 105 a direction parallel with said axis, which pin has one end arranged to co-act with the closed end of said cap-screw when the latter is screwed home on said base-member, and has its other end cam-shaped and arranged 110 to co-act with the side of the pawl and thrust the latter into its disengaged position when the pin is advanced by the cap-screw.

In testimony whereof I affix my signature. 115
HENRY FAIRBANK.
